UNITED STATES PATENT OFFICE.

PAUL WHITING, OF EAST LAS VEGAS, TERRITORY OF NEW MEXICO.

EQUALIZING-VALVE.

SPECIFICATION forming part of Letters Patent No. 707,476, dated August 19, 1902.

Application filed October 8, 1901. Serial No. 77,970. (No model.)

To all whom it may concern:

Be it known that I, PAUL WHITING, a citizen of the United States, residing at East Las Vegas, in the county of San Miguel and Territory of New Mexico, have invented new and useful Improvements in Equalizing-Valves, of which the following is a specification.

My invention relates to an equalizing-valve for air-brake systems; and the object of the same is to construct a valve which, in combination with two of my cylinder-valves covered by Letters Patent No. 679,247, dated July 23, 1901, will give the engineer perfect control of an automatic air-brake system.

The novel construction of my equalizing-valve is fully described in this specification and claimed, and illustrated in the accompanying drawings, forming a part thereof, in which—

Figure 1 is a vertical longitudinal section of my cylinder and equalizer valves. Fig. 2 is a section on the line 2-2, Fig. 1, looking toward the left. Fig. 3 is an end view of the large cylinder-valve. Fig. 4 is a development of the casing of the same. Fig. 5 is a development of the lower half of the cylinder of the same. Fig. 6 is an end view of the small cylinder-valve. Fig. 7 is a development of the casing of the same. Fig. 8 is a development of the cylinder of the same.

Like characters of reference designate like parts in the different views of the drawings.

The numeral 1 designates the casing of my large cylinder-valve A, which consists of two sections, an upper and a lower, (designated 1^a and 1^b, respectively.) Snugly fitting the casing 1 and mounted to turn therein on a stub-shaft 2 is a hollow cylinder 3. The shaft 2 has an end triangular in cross-section, and fitted thereon is a handle 4 for use in turning the cylinder 3. The triangle is irregular to prevent putting the handle on wrong. The handle 4 is provided with a spring-catch 5, adapted to engage a series of five lugs formed on the upper half 1^a of the casing, which lugs are designated by the numerals 6 to 10, both inclusive. The extreme lugs 6 and 10 are undercut at 6^a and 10^a, respectively, to engage and stop the catch, while the intermediate lugs 7, 8, and 9 are beveled off on the sides to enable the catch 5 to be forced to ride over them.

The lower half 1^b of the casing is provided with five ports, (designated by the numerals 11 to 15.) The port 11 is connected by a passage 16 to a pipe 17, connected to the main reservoir on the locomotive and not shown. The passage 16 also communicates with a pipe 16^a, connected to a governor. (Not shown.) The port 12 is connected to the rear chamber 60 of the lower cylinder of the equalizer-valve B by a passage 18. The port 13 is connected by a passage 19 to the upper chamber of the upper cylinder of the equalizing-valve B. The port 14 is connected by a passage 20 to 65 the forward chamber of the lower cylinder of the equalizing-valve. This passage also connects with a pipe 20^a, connected to a gage. The port 15 is the exhaust and communicates directly with the open air.

The cylinder 3 has a series of ports therein corresponding with the ports in the casing 1^b. The cylinder-ports are seven in number. Two of the cylinder-ports 11' and 11^a are located to be brought into register with the port 11 by using the handle 4, one other, 12', is located to be brought into register with the port 12 in the casing, two ports 13' and 13^a are located to be brought into register with the port 13, two ports 14' and 14^a are located 80 to be brought into register with the port 14, and the two remaining ports 15' and 15^a are located to be brought into register with the port 15 in the casing.

The equalizing-valve B consists of two main parts, an upper cylinder 22 and a lower cylinder 23, which cylinders are connected by ribs 21. The cylinder 22 is bolted to the valve A and communicates therewith, as before mentioned, by way of a passage 19. Mounted 90 within the cylinder 22 is a tightly-fitting piston 24, having packing-rings 24^a and a stem 25. The stem 25 fits snugly a casing 30, formed integral with the lower head of the cylinder 22. The lower end of the stem is 95 bored longitudinally at 27 for a portion of its length, and fitting within the bore is a shank 28, formed integral with a threaded head 29, screwed in the lower end of the casing 26. The head 29 is slotted at 30^a to provide a passage for the air and beveled off on its upper side at 29^a. The stem 25 is beveled oppositely from the head 29 and abuts the same, thereby forming a tight joint and normally closing

the slot 30 to the passage of air. The stem 25 is cut away at 31 adjacent to the head and apertured transversely at 31^a to enable the air to pass, when the piston 24 is raised, 5 through the slot and into a passage 32, communicating with the open air. This is the train-line exhaust, as will appear. The cylinders 22 and 23 communicate by means of a passage 33, formed in the casing and connecting the lower chamber of the upper cylinder with the forward chamber of the lower one. A reservoir 34 is connected to the cylinder 22 at a point above the piston 24 by a pipe 35. This tank increases the capacity of the cylinder and holds a reserve supply of air, which increases the efficiency of the valve. A bumper 36 is formed in the top of the cylinder 22, limits the movement of the piston, and keeps it from covering the pipe 35. A second bumper 20 37 on the piston 24 limits the downward movement thereof and keeps it from closing the passage 33.

The lower cylinder 23 is divided into two chambers 38 and 39 by a transverse partition 40, which chambers will be termed the "rear" and the "forward" ones, respectively. Mounted within the cylinder is a piston 41, having a packing-ring 41^a and a hollow stem 42, snugly fitting a sleeve 43, fitted within a 30 central aperture in the partition 40. The stem 42 is beveled off at 42^a and fits snugly over a hollow shank 44 and abuts the beveled inner face 45^a of the rear head 45 of the cylinder. This shank 44 is integral with the head 45 and is slotted at 46 to permit the passage of air when the stem 42 is unseated from the head. The head 45 is threaded and is adjustably fitted in the end of the cylinder 23. A squared portion 47 accommodates a wrench, 40 and a cap 48, fitted over the end of the cylinder, makes it doubly tight. To provide means for regulating the pressure necessary to displace the piston 41 from its normal forward position, a stiff spiral spring 49 is mounted on 45 the stem 42 and bears on the head 45 at one end and on a collar 49^a, integral with the stem. The tension of the spring can be adjusted by means of the adjustable head 45. The collar 49^a also limits the travel of the piston. As 50 before mentioned, the cylinder-valve A and the rear compartment 38 of the cylinder 23 are connected at port 12 by the passage 18, and the forward compartment 39 is connected to the valve A at port 14 by the passage 20. 55 The compartment 39 is also connected to the main train-line (not shown) by a pipe 50. The pipe 17, before mentioned, which communicates with the passage 16, is coupled to the bottom of the cylinder 23. The passage 16 60 traverses the casing of the cylinder, but has no connection with the interior thereof.

The second small cylinder-valve (designated C) is similar in construction to the valve A and is bolted to the connecting-casing just below 65 the valve A. The valve C comprises a casing 51, having upper and lower portions 51^a and 51^b, respectively, and a cylinder 52, fitted

therein. The lower half 51^b of the casing is provided with three ports, an exhaust-port 53 and two other ports 54 and 55. A pipe 56 70 communicates with the port 54 and is connected to the auxiliary train-line which supplies straight air to the brake-cylinders. The port 55 communicates with a passage 57, which in turn communicates with the passage 16, 75 connected to a pipe 17, connected to the main reservoir.

The cylinder 52 is pierced by eight ports, four large and four small ones. Four of the ports, two large and two small, are designed 80 to register with the port 54 and are designated by the characters 54', 54², 54³, and 54⁴. Two of the remaining four ports, a large and a small one, are designed to register with the exhaust-port 53 and are designated 53' and 85 53², while the other ports, a large and a small one, are located to register with the port 55 and are denoted by the characters 55' and 55². The upper half 51^a of the casing has five lugs 90 formed thereon, which are numbered from 58 to 62, inclusive. The two extreme lugs 58 and 62 are undercut. A handle 63 is connected to a stub-shaft 64 in the cylinder and provided with a spring-actuated catch 65, which is adapted to ride over the lugs 59, 60, and 61 95 and to engage the lugs 58 and 62.

The operation of my three valves A, B, and C will now be set forth and the course of the air traced with the handles on the cylinder-valves in their different positions. With the 100 handle 4 pushed over to its extreme position, with the catch 5 engaging the undercut lug 6, the valve A is in the first position. This gives the emergency action of the brakes. Ports 14 14' and the exhaust-ports 15 15' now 105 register. The air can then flow from train-line through pipe 50 into compartment 39 of cylinder 23, through passage 20 and ports 14 14' to cylinder 2, and then through ports 15 15' to open air. With the catch 5 abutting 110 the lug 7 the valve A is in the second position. The ports 13 13' and exhaust-port 15 15² now register, and air in the cylinder 22 above the piston and in the reservoir 34 flows through passage 19, ports 13 13', and ports 15 15² to open air until the pressure in the train-line, acting on the piston 24 through pipe 50, chamber 39, and passage 33, raises the piston 24. All the air might be released, if desired. This action permits the air from train-line to 115 enter the slots 30, then around the cut-away portion 31 of the stem 25, and escape to the open air through passage 32, giving an exhaust and setting brakes. When the pressure in the train-line becomes reduced to that of the air 120 remaining in the reservoir 35, the piston 24 will be again seated and the escape of air shut off. When the handle 4 stands on the center, as shown in the drawings, with the catch 5 abutting lug 8, we have the third position. The 130 ports in the cylinder 2 are all lapped. When the handle is moved over the lug 8 toward 9, the three pairs of ports 11 11', 12 12', and 13 13² begin to coincide, and when the catch 5 abuts the

lug 9 we have the fourth position, and these ports all register. Air can now pass from the main reservoir (not shown) through the pipe 17, connected to the bottom of valve 23, 5 through the passage 16, and into the cylinder-valve by way of ports 11 11' and out by way of ports 12 12', down through passage 18 into the rear compartment 38 of the cylinder 23, also down through ports 13 13' and passage 19 to cylinder 22. Since the stem 42 is normally unseated from the head 45, the air will pass from chamber 38 through slots 46, through the hollow stem 42 into chamber 39, then into the train-line through the pipe 50, releasing the 15 brakes, and also into the cylinder 22 by way of the passage 33. The admission of air beneath the piston 24 will not raise it, since air at the same pressure is also admitted above the piston by means of ports 13 13' and passage 19, from whence it passes into the reservoir 34 by way of pipe 35. This is the running position of the system. With the apparatus in the condition described above, as soon as the pressure of air in the train-line reaches 25 a predetermined intensity, equal to the adjusted tension of the spring 49, the piston 41 will seat the stem 42, thereby shutting off the access of the air to chamber 39 and the train-line; but if from leakage the pressure in the 30 train-line should be diminished the stem 42 would be again unseated and the supply renewed. Therefore when the valve A is set in this position, with the catch abutting lug 9, the valve B automatically equalizes the train-line and main-reservoir pressure—that is, it 35 restores the pressure in the train-line to its normal, which is equal to the adjusted expansive force of the spring 49. When the handle is moved over with the catch 5 engaging lug 10, this is the fifth position, and the pairs of ports 11 11' and 14 14' now register. This position gives a quick recharge and full release, as the air passes from main reservoir through pipe 17, passage 16, ports 11 11' to 40 cylinder, and out through ports 14 14', passage 20, through chamber 39 and pipe 50 to train-line. This completes the positions of the valve A, and those of the valve C will now be taken up. The first position of the valve 45 C is obtained when the handle 63 is moved over with the catch 65 engaging the lug 58. In this position the exhaust-ports 53 53' and the ports 54 54' register. This gives a rapid exhaust from the brake-cylinders by way of the auxiliary train-line, the pipe 56, and the ports 54 54' and 53 53'. This is the full-release position. The second position results 50 from setting the handle 63 at the lugs 59. The ports 53 53' and 54 54' then register and 55 give a less rapid exhaust in the same manner as before. The third position results from setting the handle 63 on the center adjacent to lug 60. All ports are then lapped. The fourth position is given by setting the handle 63 adjacent to the lug 61. This registers the ports 54 54' and 55 55' and a small supply of air to the brake-cylinders, which supply passes

into them from the main reservoir by way of pipe 17, passage 16, passage 57, ports 55 55', through cylinder to ports 54 54', and pipe 56. 70 This is an emergency position. The fifth position results from moving the handle 63 until the catch 65 engages the lug 62. This registers the ports 54 54' and 55 55' and gives a large supply to the brake-cylinders, which 75 passes into them by way of pipe 17, passage 16, passage 57, ports 55 55', ports 54 54', and pipe 56. This is the second emergency position.

From the foregoing it is evident that every 80 emergency is provided for by means of any equalizing-valve B in combination with my cylinder-valves A and C.

I do not wish to be limited as to details of construction, as these may be modified in 85 many particulars without departing from the spirit of my invention.

Having thus described my invention, what I claim as new, and wish to secure by Letters Patent, is—

1. In a valve of the class described, the combination of a cylinder divided into front and rear compartments by a transverse partition, an adjustable head fitted into the rear end of said cylinder and provided with a stem, a 95 piston located in said front compartment and having a hollow stem mounted in said partition and fitting over said stem, and a spring mounted on said hollow stem and bearing on said adjustable head, substantially as described. 100

2. In a valve of the class described, the combination of a cylinder divided into front and rear compartments by a transverse partition, an adjustable head fitted into the rear end 105 of said cylinder and having a grooved stem, a piston located in said forward compartment and having a hollow stem slidingly mounted in said partition, and fitting over said stem, and a spring mounted on said hollow stem, substantially as described. 110

3. In a valve of the class described, the combination of a casing divided into front and rear compartments by a transverse partition, each of said compartments having an air-passage connected thereto, a piston mounted in said front compartment and having a hollow stem which is slidingly mounted in said partition, a valve-seat located in said rear compartment in position to close said hollow 115 stem when seated thereon, a spring mounted on said hollow stem and arranged to hold it normally unseated, and a cylinder-valve comprising an outer and inner cylinder having ports located to be brought into register by 120 turning said inner cylinder, said cylinder-valve being connected to regulate the flow of air through said air-passage, substantially as described. 125

4. In a valve of the class described, the combination of a lower cylinder divided into front and rear compartments by a transverse partition, a valve-seat mounted in said rear compartment, a piston mounted in said front

- compartment and provided with a hollow stem slidingly mounted in said partition and constructed to fit said seat, a spring surrounding said stem and arranged to normally hold it unseated, an exhaust-passage connected to said front compartment, an upper cylinder a piston mounted in said upper cylinder and provided with a stem constructed to regulate the exhaust of air through said passage, a passage connecting said upper and lower cylinder, air-passages connected to said upper cylinder and to the front and rear compartment of said lower cylinder, and means for regulating the flow of air through said passages, substantially as described.
5. In a valve of the class described, the combination of a lower cylinder divided into front and rear compartments by a transverse partition, a valve-seat mounted in said rear compartment, a piston mounted in said front compartment and provided with a hollow stem slidingly mounted in said partition and constructed to fit said seat, a spring constructed to normally hold said stem unseated, an air-passage connected to said rear compartment, means for regulating the flow of air through said passage, a pipe and an exhaust-passage connected to said front compartment, an upper cylinder, a piston mounted in said upper cylinder and provided with a stem constructed to serve as a valve to regulate the flow of air through said exhaust-passage, and an air-passage connecting said upper cylinder and said forward compartment, substantially as described.
10. In a valve of the class described, the combination of a lower cylinder comprising front and rear compartments, a valve-seat mounted in said rear compartment, a piston mounted in said front compartment and provided with a hollow stem extending into said rear compartment and constructed to fit said seat, a spring mounted to normally hold said stem unseated, an exhaust-passage and a pipe connected to said front compartment, an upper cylinder, a piston mounted in said upper cylinder and provided with a stem constructed to serve as a valve to regulate the flow of air through said exhaust, a reservoir connected to said upper cylinder to increase the capacity thereof, air-passages connected to said rear compartment and said upper cylinder, means for regulating the flow of air through said passages, and an air-passage connecting said upper cylinder and said front compartment, substantially as described.
15. In a valve of the class described, the combination with a cylinder, of a piston mounted in said cylinder and having a hollow stem forming a valve, a valve-seat located to coöperate with said hollow stem to regulate the flow of air from one side of said piston to the other, a spring mounted to regulate the amount of pressure necessary to move said piston to operate said valve, a passage connecting said cylinder to the open air, a second cylinder, connected to said first-mentioned cylinder by a passage, a piston mounted in said second cylinder and provided with a stem constructed to serve as a valve to open and close said passage to the open air, substantially as described.
20. In a valve of the class described, the combination with a cylinder, of a piston mounted in said cylinder and having a hollow stem, a valve-seat mounted to close said stem when seated thereon, a spring mounted to oppose the seating of said hollow stem on said valve-seat, a main reservoir connected to said cylinder in the rear of said piston, a train-line connected to said cylinder at a point in front of said piston, a second cylinder, a piston mounted in said cylinder and bearing a stem mounted to serve as a valve to open and close an exhaust-passage communicating with the forward end of said first-mentioned cylinder, said second cylinder being connected to said first-mentioned cylinder at a point in front of the said piston therein, and means for regulating the flow of air into and out of said second cylinder, substantially as described.
25. In testimony whereof I have hereunto set my hand in presence of two subscribing witnesses.
